UNITED STATES PATENT OFFICE.

CHARLES L. GARGAN AND JOSEPH EUSTACE LEINEN, OF ROCHESTER, NEW YORK, AS
SIGNORS TO CHARLES D. LEONARD, OF ROCHESTER, NEW YORK.

STOVEPIPE DAMPER.

Application filed September 17, 1921. Serial No. 501,388.

To all whom it may concern:

Be it known that we, CHARLES L. GARGAN and JOSEPH EUSTACE LEINEN, both of Rochester, in the county of Monroe and State of New York, have invented certain new and useful Improvements in Stovepipe Dampers; and we do hereby declare the following to be a full, clear, and exact description of the same, reference being had to the accompanying drawing, forming a part of this specification, and to the reference numerals marked thereon.

This invention has to do with dampers for regulating the combustion of fuel in stoves, ranges, furnaces and the like, relating more particularly to damper appliances for flues or draft pipes for controlling the draft therein. The chief object of the invention is to provide practical and effective apparatus of the above character for so controlling the amount of draft as to promote efficiency and economy in the combustion of the fuel, for preventing the discharge of gases into the room in which the fire is located, and for preventing back drafts into the fire pot. A further object is to provide apparatus of the above character which may be readily applied to any draft pipe and conveniently operated for the purposes stated. To these and other ends the invention consists in certain improvements and combinations of parts, all as will be hereinafter more fully described, the novel features being pointed out in the claims at the end of the specification.

In the drawing:

Figure 1 is a plan view of apparatus embodying the present invention showing its application to an ordinary draft pipe;

Figures 2 and 3 are sectional views of the same taken longitudinally of the pipe and showing the operating parts in different positions;

Figure 4 is a sectional view on the line 4^a—4^a of Figure 3; and

Figure 5 is a detailed sectional view on the line 5^a—5^a of Figure 3.

Similar reference numerals throughout the several views indicate the same parts.

The embodiment of the invention disclosed in the present instance by way of illustration of the principles involved and a preferred practical application of the same is shown as applied to an ordinary draft pipe 10 in which is cut a lateral opening or vent 11. The regulating apparatus is preferably

supported as a unit on a sheet metal plate 12 curved to fit the pipe exterior and having at its opposite edges perforations 13 in which are engaged the ends of straps 14 embracing the pipe for detachably securing plate 12 thereto. Plate 12 is formed with an opening of substantially the size of the lateral opening in the draft pipe surrounded by a flange adapted to project into the pipe through its lateral opening. This flange is preferably formed by striking up the material of plate 12 on opposite sides of the opening as at 15^a, and connecting flange plates 15^a at the remaining sides of the opening with similar flange plates 15^b, these flange sides preferably terminating in a common plane parallel with the axis of the pipe.

Means are preferably provided for pivotally supporting a damper at one side of the flanged lateral opening in the pipe described above so that it may be swung either against the flange of the opening to close the latter, in which case the draft in the pipe is unobstructed, or else laterally of the pipe to obstruct the draft with the lateral opening or vent uncovered. Such means comprises, preferably, an angular length of relatively stiff wire 16, Figures 2 and 4, located within the flanged opening and projecting at its ends 17 through perforations in the side flanges 15^a adjacent one of the sides 15^b. Pivotally supported on the ends of the wire 16 are spaced upstanding ears 18 carried by a main damper plate 19 preferably of less width in a direction perpendicular to its pivotal axis than the diameter of the pipe, Figure 4, but of sufficient area to cover and close the lateral opening of the pipe when moved against the flange as indicated in Figure 2. It is apparent from this construction that damper plate 19 may be swung on its pivot from the position shown in Figure 2 in which it closes the lateral opening of the pipe, to the position shown in Figures 3 and 4 in which the lateral pipe opening is uncovered and the damper extends transversely of the pipe in position to obstruct the draft through the same.

The means for swinging the damper from one position to another comprises preferably a threaded post or stud 20, Figure 2, passed through an opening in damper plate 19 and adjustably clamped to the same by means of nuts 21, the upper end of the post hav-

ing pivotally attached thereto a link 22 pivoted at its other end 23 to an arm 24 of an angular lever pivotally supported at 25 on a bracket 26 fixed on the plate 12. The other arm 27 of the lever is adapted for the attachment thereto of a cord or other flexible element 28 passing around a pulley 29 carried by a bracket 30 on the opposite side of plate 12, from which the cord may be carried to any suitable point from which it is desired to control the regulating apparatus. A coil spring 31 fixed at one end to the outer end 23 of link 22 and at its other end to bracket 26 tends to move damper plate 19 to a position to open the draft pipe and close its lateral opening.

The damper preferably comprises a plurality of relatively movable parts or plates with means for adjusting the same to vary the degree of obstruction of the draft in the pipe, and also for adapting the damper to pipes of different sizes. To this end there is employed in addition to the main damper plate 19 a plate 32 arranged in parallel overlapping relation with the plate 19 and adapted to extend therefrom so as to substantially complete the closing of the pipe when moved to a position transverse of the same. Plate 32 is supported on plate 19 by means of a post 33 fixed to plate 32 and extending perpendicularly to the latter through an elongated slot 34, Figures 4 and 5, formed in plate 19 perpendicular to the axis of support of the latter. Post 33 carries on the opposite side of plate 19 a wing headed bolt or screw 35 rotating freely in the post and extending through an elongated slot 36 in a post 37 adjustably carried by plate 19. Screw 35 carries a nut 38 bearing against the other side of post 37. It is apparent from this construction that when the clamping connection between posts 33 and 37 is loosened plate 32 may be moved toward and from plate 19. When adjusted to the position shown in Figure 2 these plates form in effect a single damper plate but as shown in Figure 3, plate 32 may be secured in spaced relation to plate 19, the overlapping relation of the plates providing a circuitous passage for the draft therebetween. This passage may be varied to control the degree of draft permitted by adjustment of plate 32 to different distances from plate 19 as described.

Means are also provided for extending plate 32 to different distances beyond the outer edge of plate 19 to adapt the damper to fit pipes of different diameters, comprising preferably a supporting plate 39 for post 37 adjustably carried on plate 19. Plate 39 to this end has formed therein an elongated slot 40 parallel with slot 34, Figure 4, the sides of which slidably engage a bolt or screw 41 fixed in plate 19 and provided with a nut 42 for clamping plate 39

in different positions of adjustment on plate 19. Plate 39, adjacent the base of the post 37 carried thereby, is provided with projecting portions or shoulders 43, Figure 4, slidably embracing the opposite sides of post 33 so that when nut 42 is loosened post 33 may be moved longitudinally in slot 34 while plate 39 slides on bolt 41, the damper plate 32 being thus moved toward and from the pivotal support of plate 19 and clamped in adjusted position by means of nut 42. As shown in Figure 4 the damper plates are preferably formed at the intermediate opposite sides with straight portions spaced from the pipe walls to prevent the complete shutting off of the draft so as to provide for a slight draft when the damper is closed to avoid discharge of gases into the room in which the fire is located.

There is provided also an adjustable closure for the lateral pipe opening comprising preferably a plate 44 of sheet metal having its sides bent angularly as at 45 to engage resiliently between the opposite flanged sides of the lateral opening to hold the closure 44 in place. The ends of the flanges 45 at one side of the closure, preferably that adjacent the damper, are curved at 46 as shown in Figure 3, to facilitate adjusting the position of the closure in the flanged opening to vary the degree of closure of the same, the resilient sides 45 of the closure holding it in adjusted position. The closure may be partially cut away as at 47 to afford clearance for the devices for operating the damper. The closure may be provided with any suitable projection as at 48 serving as a handle.

In operation, plate 12 carrying the apparatus is applied over a lateral opening in the draft pipe with its flanges extending into the latter and is detachably secured to the pipe by means of the strips 14. Damper plate 32 is adjusted parallel with plate 19 to suit the diameter of the pipe and is also adjusted toward and from plate 19 in accordance with the degree to which it is desired to obstruct the draft, access to the adjusting means for this purpose being conveniently had through the lateral pipe opening. Closure 44 of the lateral opening is adjusted in the manner indicated in Figure 3 depending upon the extent to which it is desired to vent the pipe. Spring 31 normally moves the damper to the position shown in Figure 2 in which the lateral opening or vent of the pipe is closed and the draft unobstructed. By means of cord 28, however, the damper may be moved to and secured in any intermediate position, it being apparent that the lateral opening is uncovered by the damper as the latter is moved toward draft obstructing position, the closure 44 serving to regulate the de-

gree of obstruction of the lateral opening when the damper is moved to obstruct the pipe.

The apparatus thus provides a simple, practical and effective construction for the regulation of the degree of draft which is selected with reference to the condition of the fire. The movement of the damper away from the vent or lateral opening of the pipe 10 serves to admit air through the latter as determined by the adjustment of closure 44 to reduce the draft acting on the fire pot, and the damper plates may be relatively adjusted toward and from each other in conjunction with the adjustment of closure 44 to accurately control the degree of draft. The apparatus thus provides means for restricting excessive flow of the heated gases up the pipe, thus preventing too rapid combustion of the fuel and a waste of heat through the pipe, as well as the carrying off of unburned fuel likely to produce objectionable smoke. At the same time the flue or pipe may be so regulated as to maintain a sufficient draft for the complete combustion of the fuel and the apparatus affords a degree of control largely obviating the necessity for adjustment of the other draft means or doors usually provided in a stove 20 or furnace. The parts are so constructed and arranged that when suitably adjusted a considerable degree of draft may be permitted up the pipe while at the same time any back draft down the pipe is arrested by the circuitous path formed by the damper and by the upward flow of gases past the same, and is deflected outwardly through the lateral opening in the pipe preventing the entrance of the same into the fire box. The construction is economical to manufacture, and may be readily applied to any ordinary draft pipe.

We claim as our invention:

1. In a device of the class described, the combination with a draft pipe having a lateral opening therein of a damper supported in the pipe adjacent said lateral opening for movement to selectively obstruct said opening or said pipe and comprising a plurality of plates each adapted to partially close said pipe, and means for adjusting the position of one of said plates on the damper to vary the degree of obstruction of the draft when said damper is moved to draft obstructing position.

2. In a device of the class described, the combination with a draft pipe having a lateral opening therein of a damper movably supported in the pipe adjacent said lateral opening for closing said lateral opening in one position and for obstructing said pipe in another position, and an adjustable closure for variably obstructing said lateral opening when said damper is in said pipe obstructing position.

3. In a device of the class described, the combination with a draft pipe having a lateral opening therein of a damper movably supported in the pipe adjacent said lateral opening for closing said lateral opening in one position and for obstructing said pipe in another position, said damper comprising a plurality of plates each adapted to partially close said pipe and one of which is adjustable on the damper to vary the degree of obstruction of said pipe, and an adjustable closure for variably obstructing said lateral opening when said damper is in said pipe obstructing position.

4. In a device of the class described, the combination with a draft pipe having a lateral opening therein of a damper plate movably supported in said pipe adjacent said lateral opening and adapted in one position to close said opening and in another position to extend partially across the pipe interior, a second plate arranged in parallel overlapping relation with the first to extend across the remainder of the pipe interior, and means supporting said second plate for movement toward and from the first to provide a variable draft passage therebetween and for movement parallel with said first plate transversely of the pipe.

5. In a device of the class described, the combination with a draft pipe having a lateral opening therein of a damper provided with an adjustable part and movably supported in the pipe adjacent said lateral opening to control the draft in the pipe and also said opening, a lever pivotally supported on the pipe, a link connecting said lever and damper, means accessible through said lateral opening for adjusting the connection between said link and damper and for adjusting said part on the damper, and a movable cover for said lateral opening.
